Attorney—Stowell and Stowell

ABSTRACT: A body supported granular material spreader is provided by a container which receives the granular material. The bottom wall of the container communicates with a depending outlet conduit having a butterfly-type valve mounted therein. The butterfly valve is actuated by a lever and cooperating stop means associated with a wall of the container and with the lever permit opening of the spreader valve between a closed position and a full open position at a plurality of intermediate positions. The spreader is also provided with depending legs which extend a distance greater than the length of the outlet conduit so that the spreader is self-supporting when it is not in use or for filling purposes.

BODY SUPPORTED GRANULAR MATERIAL SPREADER

BACKGROUND OF THE INVENTION

Granular material dispensers and spreaders are known in which valve means are provided for dispensing granular material maintained in a hand or body carriage support. Such devices of the prior art generally do not permit presetting of the rate of flow of the granular material and the convenience of being self-supporting when not in use.

THE PRESENT INVENTION

It is a principal object of the present invention to provide a simple, relatively inexpensive spreader for granular fluent material adapted to the supported by the body of the user.

It is another object of the present invention to provide such a device wherein a single actuating lever opens a flow control valve and means are associated with the lever to provide stop means for regulating the amount of flow from the spreader.

Another object of the invention is to provide a body supported granular material spreader wherein legs depend from the spreader a distance greater than a fixed outlet so that the spreader is self-supporting, in an upright position, when the spreader is not in use.

Other objects and advantages of the invention are provided by a body supported granular material spreader comprising a walled container adapted to receive granular fluid material, an outlet conduit in the bottom thereof communicating with the interior of the container, a valve in the outlet conduit having a closed position, an open position, and intermediate positions between the open and closed positions, an actuating lever for said valve, and stop means cooperating with the wall of the container and with the actuating lever to limit movement thereof and to determine the valve setting.

The invention will be more particularly described in reference to the accompanying drawings wherein:

FIG. 1 is a perspective view of a preferred embodiment of the granular material spreader of the invention with the cover or like in the open position;

FIG. 2 is a top plan view of the structures illustrated in FIGURE 1;

FIG. 3 is a fragmentary vertical sectional view taken from line 3—3 of FIGURE 2; and

FIG. 4 is a fragmentary partial sectional view of the outlet conduit and conduit extension means for the device illustrated in FIGS. 1 through 3.

Referring to the drawing, 10 generally designates an improved body supported granular material spreader which includes a container 12 having end and bottom walls, a cover 14; an outlet spout generally designated 16 at the lower end of the bottom wall, valve control means 18 and a flexible draft member 20 connected at its ends to the sidewalls so that the spreader may be conveniently carried by the body of the user.

As illustrated in the drawing the container 12 includes a generally semicylindrical wall portion 22 and a pair of flat sidewalls 24 and 26 secured thereto such as by welding, if the container is formed of metal. It will be recognized by those skilled in the art that the material of construction is not critical and the entire container 12 may be cast or molded from, for example, high impact plastic.

Centrally secured in the lower barrel portion of the wall 22 is an outlet conduit 28 forming a portion of the outlet spout 16 as more clearly illustrated in FIGS. 3 and 4 of the drawings. Since the wall 22 slopes towards the outlet 16 mechanical agitators, stirrers and the like are not required to maintain a substantially uniformed flow of granular material from the container. The cover 14 is counted to the sidewall 24 by hinges 30 shown, for example, in FIGS. 1 and 3 of the drawings.

Mounted within the outlet conduit 28 is a flow control valve member generally designated 32. The flow control valve mechanism 32 includes a plate member 34 provided with generally depending wings 36 which wings are formed to

receive a pivot pin 38. The wings are secured to the pin 38 by for example welding so that when the pin 38 is rotated the plate 34 is moved from the closed position illustrated in FIG. 3 and 4 to an open position.

One end of the pin 38 extends laterally beyond the sidewall 26 of the container 12 and, receives on the extended end thereof an operating lever 40. The lever 40 is attached by, for example, a screw fastener 42 which holds the lever 40 onto a squared portion of the shaft 38, not shown in the drawing, whereby movement of the lever 40 via the handle portion 44 causes the butterfly-type valve 32 to operate.

In a preferred form of the invention the control valve 32 is in the fully closed position when the plate 34 thereof is at approximately the 45° position with the horizontal.

In the illustrated form of the invention a plate member 48 is secured to the upper lateral edge of sidewall 26 by for example screw-type fasteners 50. The plate 48 carries a pair of fixed pins or pegs 52 and 54 and the length of the pegs 52 and 54 are such that they engage the operating lever 40 as more clearly shown in FIGS. 1 and 2 of the drawing.

Peg 52 represents that position of the lever 40 when the valve is fully closed and peg 54 represents the stop position for lever 40 when the flow control valve 32 is in the full open position. The bar 48 is also provided with a plurality of bores or openings designated 56, 58 and 60 which bores or openings are adapted to receive the cylindrical end 62 of a stop peg 64 which stop peg is attached by a flexible draft member 66 to the plate 48 as at 68. Indicia, such as shown at A, FIG. 3, of the drawing may be placed under the bores 56, 58 and 60 to indicate to the user the approximate rate of flow of material from the container 10 when the peg or stop member 64 is positioned in such openings.

While the positive releasable peg is employed as the flow control setting means for the valve in conjunction with the operating lever it will be apparent to those skilled in the art that the removable peg stop could be replaced by a spring-type detent members either carried by the lever 40 and adapted to engage the openings 56, 58 and 60 or the detents might replace the openings 56, 58 and 60 and engage a socket on the inner surface of the operating lever 40. While such "click stop" detent means would permit the operator of the device to quickly shift from, for example, light or medium to the heavy flow operating position, such stops are not as positive as the illustrated peg stop means.

The assembly also includes a pair of legs or support members 72 and 74 which are secured to the curved portion of the sidewall 22 by screws or the like shown more clearly in FIG. 2 of the drawing. The length of the legs 72 and 74 are selected to be greater than the length X, FIG. 4, of the discharge spout 28 so that the device may be rested upon the legs when the device is being filed or when it is not otherwise in use. In order to modify or improve the distribution of the granular fluent material an auxiliary spout 80 may be provided. The auxiliary spout is provided with a type slot attaching means 82 which is receivable about the outward extension of the pin or peg 38 whereby the discharge conduit extension may be readily applied or removed by the operator.

While a nontelescopic-type discharge tube is illustrated in the drawings it will be recognized that an accordion or telescopic-type tube extension may be employed with the device so that removal of the tube is not necessary when it is desired to rest the spreader on its feet 72 and 74.

In an preferred embodiment of the spreader of the invention, particularly adapted for depositing fertilizer on lawns or the like, the container 12 has a width of 8 inches; a length across the top of 14 inches and a depth at the center of 9½ inches. Further with a spreader having a container size as disclosed above a discharge conduit having a diameter of three-fourths of an inch with a discharge tube extension of 12 was found to be very satisfactory.

From the foregoing description of a preferred embodiment of my invention it will be recognized by those skilled in the art that various modifications may be made in the device with out departing from the scope of the appended claims.

I claim:

1. A body supported granular material spreader comprising a container body having opposing substantially flat sidewalls, opposing end walls, a bottom wall and an open top and adapted to house a free flowing supply of granular material, means carried by the end walls for engaging the body of a user so that the container body is supported by a user's body in a substantially vertical position with one sidewall being innermost toward the user's body and the other sidewall being outermost from the user's body, a gravitational discharge means provided on the bottom wall in communication with the interior of the container body, a shaft transversely arranged and rotatably mounted in said discharge means, a valve plate operatively positioned in the discharge means and carried by the shaft, said shaft having an end portion extending beyond the outer sidewall, an actuating lever disposed alongside and parallel with the outer sidewall and having a lower end portion connected to the extended end portion of the shaft and having an upper end portion defining a handle portion and disposed above the top of the container body, said lever being moved in a curvilinear path by the user's hand engaging the handle portion above the top of the container body and moving the valve plate from a closed to a fully open position and to intermediate open positions between the closed and fully open positions, said outer sidewall having a plate member fixed thereon adjacent its upper end and parallel with the top, said plate member having opposing end portions adjacent the end

walls, stop pegs carried by said end portions and extending outwardly from the outer side wall normal to the path of movement of the lever and defining positive stops for limiting travel of the lever toward the opposing ends of the container body, said lever when engaged with one stop peg locating the valve plate in a fully closed position and when engaged with the other stop peg locating the valve plate in a fully open position, said plate member being formed intermediate its end portions with transverse bores arranged normal to the outer sidewall, said bores being spaced apart along the long axis of the plate member, a removable stop peg adapted to be fitted into a selected bore in opposing relation to the fully closed stop peg so as to be engaged by the lever in its valve opening movement and positively located the valve plate in one intermediate open position and tether means connected between the removable stop peg and the plate member.

2. The invention of claim 1 wherein said user's body engaging means carried by the end walls of the container body includes a flexible strap having opposing ends anchored to the end walls of the container body adjacent the top thereof.

3. The invention of claim 1 wherein a closure lid is provided for said open top and hinge means carried by the inner sidewall and connecting the closure lid to the container body.

4. The invention of claim 1 wherein said tether means includes an elongated flexible element anchored to the plate member and carrying the removable stop peg.
